UNITED STATES PATENT OFFICE.

PHILIP VINCENT, OF OLYMPIA, WASHINGTON.

SELF-DUMPING SCOW.

Application filed November 4, 1924. Serial No. 747,356.

To all whom it may concern:

Be it known that I, PHILIP VINCENT, a citizen of the United States, and a resident of Olympia, in the county of Thurston and 5 State of Washington, have invented certain new and useful Improvements in Self-Dumping Scows, of which the following is a specification.

My present invention relates generally to 10 scows, and my object is the provision of a scow so constructed and adapted to be operated as to form an effective self-dumping arrangement which will obviate the usual cost and delays in unloading, especially the 15 dumping of garbage and filling materials which are to be unloaded in the water.

In the accompanying drawings which illustrate my present invention and form a part of this specification,

20 Figure 1 is a partial side view of a scow constructed in accordance with my invention.

Figure 2 is a partial longitudinal section therethrough,

25 Figure 3 is a vertical transverse section taken therethrough, and

Figure 4 is a partial top plan view thereof.

Referring now to these figures my invention proposes a scow including a reversible hull, the opposed decks 10 and 11 of which form the top and bottom depending upon which way the reversible hull is turned. These decks 10 and 11 are spaced apart by the hull sides 12 and also by a 35 longitudinally central partition wall 13, the latter of which divides the entire hull into separate side compartments 14 and 15. Each of these compartments 14 and 15 has a false bottom, the bottom 16 of the compartment 14 being adjacent to the deck 11 and the bottom 17 of the compartment 15 being adjacent to the deck 10, these false compartments forming between the same and the decks adjacent to which they extend, air 40 spaces 18 and 19. The compartments 14 and 15 are water compartments and it is contemplated that the partition wall 13 and the false bottoms 16 and 17 will be caulked like the hull sides 12 so that there will be 45 no intercommunication between the compartments 14 and 15 or between these air compartments and the air chambers 18 and 19. Where there is any leakage of water into the air chambers 18 and 19, this may be 50 displaced through normally closed drain

pipes 20 communicating with these chambers through the hull sides 12.

Opening through the hull sides 12 into each of the water chambers 14 and 15 are water inlet and outlet openings normally 60 closed by outwardly opening valves 21, each of these valves adapted to be opened by a rod 22 extending transversely through the hull with a handle 23 beyond the opposite hull side with respect to which the particular valve is mounted.

At its opposite ends the hull is oppositely curved as seen at 24 in Figures 1 and 2, the two decks being preferably provided with stringers 25 and also having side bulwarks 26 including uprights or stanchions 27, the latter of which are hinged at their lower ends as at 28 to the decks so that these bulwarks are free to fold inwardly against the deck as indicated in the lower portion 75 of Figure 3 when the latter is turned downwardly.

It is also to be noted that the water inlet and outlet valve 21 of each water chamber is located immediately adjacent to 80 the false bottom of that chamber and that each water chamber has a valved air outlet 29 opening through its false bottom and through the deck adjacent to which its false bottom is mounted, the false bottom of each 85 of the water chambers 14 and 15 being disposed therein at a point above the water line of the hull when the scow is unloaded.

In Figure 3 I have shown the hull of the scow deep in the water as it will appear when 90 loaded, the deck 10 being uppermost with the load thereon between the upstanding bulwarks 26. To cause the scow to dump, assuming at this time that both of the water chambers 14 and 15 are free of water, the 95 handle 23 of the rod 22 controlling the water inlet and outlet valve 21 of the water chamber 15, is actuated to open said valve 21 so that water is free to enter the chamber 15, the valved inlet port of which is at that time 100 below the water level with the scow loaded and the hull deep in the water as shown. Water enters the water chamber 15 at one side of the longitudinal center of the hull, the air within this chamber being forced 105 outwardly through the air outlet 29 and the weight of the water overturns the hull on its longitudinal axis, during which overturning, the load upon the deck 10 is of course dumped into the water. During this 110

overturning the water inlet and outlet valve remains open and it is obvious that as the load is dumped the hull rises in the overturned position with the deck 11 uppermost, the 5 water line being then below the false bottom 17 of water chamber 15 so that the water previously filling the chamber is allowed to run out of the same until it is entirely clear, when the valve is closed and 10 the scow is again in position for the reception of a load upon its deck 11.

It is obvious from this that with the scow constructed as shown in Figure 3 it is always overturned to the right and for quick- 15 action in large scows it is obvious that a plurality of valved water inlet and outlet ports may be provided instead of but one for each water chamber as shown.

It is obvious that other refinements may 20 be made and that in order to relieve in part the strain upon the hinges 28 of the stanchions 27, the upper ends of these stanchions may be connected by cables, chains or other flexible connections 30 with the deck string- 25 ers 25 as shown in Figures 3 and 4.

Thus it is obvious that by providing a scow having a hull constructed as shown with lengthwise water-tight bulkheads at respectively opposite sides and adjacent to its 30 opposite decks, with the bottom of each bulkhead above the normal water line of the hull when the scow is unloaded, and together with means for opening the side inlet valves from the opposite side of the hull 35 with respect to such valve, it follows that the dumping of the scow may be accomplished with ease and facility, in such manner as to avoid the slow and more expensive methods of discharging the load that are 40 now in use.

I claim:

1. A self-dumping scow including a hull having a pair of oppositely facing decks, side walls and a central longitudinal partition wall connecting said decks and forming 45

longitudinal side compartments, each of said compartments having a false bottom, one adjacent to one of the said decks and the other adjacent to the other deck, bulwarks hinged to the side of the decks to fold inwardly therealong, each of the said longitudinal compartments having a valved water inlet and outlet through its outer side wall located adjacent to its false bottom, and each of said compartments having valved air 55 escape means extending through its false bottom and through the adjacent deck, for the purpose described.

2. A self-dumping scow including a hull having a pair of oppositely facing decks, 60 side walls and a central longitudinal partition wall connecting said decks and forming longitudinal side compartments, each of said compartments having a false bottom, one adjacent to one of the said decks and the other adjacent to the other deck, bulwarks hinged to the side of the decks to fold inwardly therealong, each of the said longitudinal compartments having a valved water inlet and outlet through its outer side 65 wall located adjacent to its false bottom, and each of said compartments having valved air escape means extending through its false bottom and through the adjacent deck, the said hull having oppositely curved 70 ends and the said false bottoms of the compartments forming between the same and the adjacent decks air spaces provided with drain plugs for the purpose described.

3. A self-dumping scow including a hull 75 having two decks opposite one another and a central longitudinal partition wall dividing the same into similar side compartments, each compartment being located adjacent to one of the decks and having a false bottom spaced from the other deck, and each compartment having a valved water inlet and outlet port located in the outer side wall thereof adjacent to its said false bottom.

PHILIP VINCENT.
